UNITED STATES PATENT OFFICE.

JOHN H. ROBERTSON, OF GRANBY, MISSOURI.

LOCK.

1,075,381.

Specification of Letters Patent.

Patented Oct. 14, 1913.

Application filed June 2, 1913. Serial No. 771,268.

To all whom it may concern:

Be it known that I, JOHN H. ROBERTSON, a citizen of the United States, residing at Granby, in the county of Newton and State 5 of Missouri, have invented certain new and useful Improvements in Locks, of which the following is a specification, reference being had to the accompanying drawings.

This invention relates to improvements in 10 door locks, and an object thereof is to simplify and improve the construction and increase the efficiency of devices of this character.

Another object of this invention is the 15 vision of a door lock which will be applicable to either hinged or sliding doors, and one which will securely hold the door in closed position.

With these and other objects in view, my 20 invention consists in the novel construction, combination and arrangement of parts, to be hereinafter more fully described, claimed and illustrated in the accompanying drawing, in which—

25 Figure 1 is a side elevation of my improved lock with the cover of the casing removed; Fig. 2 is a longitudinal section thereof; Fig. 3 is a sectional view on the line 3—3 of Fig. 1, and Fig. 4 is a perspective view of the keeper.

Referring more particularly to the drawing, the numeral 1 designates a casing which is adapted to be secured to the inner face of a door, the casing having a latch bar 2 pivotally mounted at one end therein as at 3, the free end of the latch bar projecting beyond one end of the casing and being curved downwardly as at 4, to provide a hook for engagement with a keeper 5 which is secured 35 to the jamb of the door. The keeper 5 comprises a base plate which is formed with a laterally extending keeper arm 6, the outer end of the arm being inclined downwardly as at 7, and the arm being provided inwardly 40 as at 8, of the inclined portion thereof with an opening 9. The arm 6 is provided to one side and forwardly of the opening 9 with an upstanding pin 10, the pin 10 being of substantially the same length as the bent portion of 45

50 the latch bar, whereby when the hooked portion of the latch bar engages the inclined portion of the keeper arm, the latch bar will ride upwardly thereon so that the bar passes over the upstanding pin 10, and the hooked end 4 of the bar will engage in the opening 9. When the hooked portion 4 of the bar

is engaged in the opening 9, the body portion of the bar is disposed between the base plate of the keeper and the upstanding pin 10, whereby any movement of the door is prevented.

Connected to the inner wall 11 of the casing intermediate of its ends is a guide bar 12, the intermediate portion of the guide bar being spaced from the plate 10, the opposite ends of the bar being connected to the plate. The latch bar 2 is disposed in the space between the guide bar 12 and the inner wall of the casing and the wall is provided with a key hole 13 opposite the guide 65 bar 12, the guide bar having an opening 14 in alignment with the key hole to receive the extremity of the shank of the key 15. The guide bar 12 is formed below the opening 13 with a laterally extending lug 15 of 70 any desired contour, the bit 16 of the key being provided with a notch 17 which is of the same shape as the key 15 whereby the key may be rotated so that the bit thereof may engage the latch bar and raise the 75 hooked end 4 thereof out of engagement with the opening 9 in the keeper. Connected to the inner wall 10 of the casing near its outer end is an offset and shouldered guide strap 18, the lower shoulder 19 of which forms a 80 stop to limit the downward movement of the latch bar 2. The upper wall of the guide strap 18 is provided with an opening 20 through which an upstanding pin 21, formed on the latch bar, projects, and a 85 coil spring 22 is disposed around the pin 21, one end of the spring bearing against the upper wall of the guide bar 18 and the lower end of the spring bearing against the latch bar, whereby the latch bar is forced downwardly and is held in a position to engage the inclined portion 7 of the keeper arm 6. 95

It is well known that lock springs often break, and that the broken parts often become wedged or jammed in between some of the working elements of the lock and prevent them from operating. Now, in case the spring 22 should be broken, the pin 21 and guide strap 18 effectually prevent dislodgment of the broken part from the guide pin 100 21, because of its upward extension through the apertured shoulder of the strap.

From the above description taken in connection with the accompanying drawing, it will be understood that my improved lock 110 may be used either in connection with sliding or swinging doors, and that it is adapted

to securely hold the door in closed position. Furthermore, the lock may be constructed for use in connection with an especially designed key, merely by changing the con-
formation of the laterally extending lug 15
5 on the guide bar 11.

What I claim is:

In a lock, a casing, a latch bar pivotally mounted in the casing and having an up-
10 standing pin mounted thereon, an angularly bent and shouldered guide strap hav-
ing an aperture through one of its shoul-
ders and being secured to the casing in such

manner as to embrace the lock bar and the major portion of said pin between its shoulders and to receive the upper end of said pin through its aperture, and a compression spring coiled around said pin and having its lower end seated on the latch and its upper end seated against the apertured shoulder. 15 20

In testimony whereof I hereunto affix my signature in the presence of two witnesses.

JNO. H. ROBERTSON.

Witnesses:

ALVIN R. KITTEL,
J. W. TAYLOR.
